(57) **CLAIM**

The ornamental design for a container lid with anti-spill spout, as shown and described.

DESCRIPTION

FIG. 1 is an upper, front, left side perspective view of a container lid showing my new design;

FIG. 2 is a top plan view thereof;

FIG. 3 is a bottom plan view thereof;

FIG. 4 is a left side elevational view thereof; the right side is a mirror image thereof;

FIG. 5 is a front elevational view thereof;

FIG. 6 is a rear side elevational view thereof;

FIG. 7 is a cross-sectional view of FIG. 2 taken along the lines 7—7 showing two container lids in a nested configuration;

FIG. 8 is a left side elevational view thereof; the broken lines show the lid mounted on a cup; and,

FIG. 9 is an upper, front, left side perspective view of a container lid showing an alternative embodiment of my new design.

The broken lines are for illustrative purposes only and form no part of the claimed design.
